(57) **CLAIM**

We claim the ornamental design for a securing device for cannula attachment to syringe body, substantially as shown and described.

DESCRIPTION

FIG. 1 is a perspective view of a cannula securing device showing my new design;

FIG. 2 is a bottom perspective view thereof;

FIG. 3 is a top perspective view thereof;

FIG. 4 is a side view thereof;

FIG. 5 is a side view thereof;

FIG. 6 is a front view thereof;

FIG. 7 is a back view thereof; and,

FIG. 8 provides a perspective view of the cannula securing device of FIG. 1 as it would be placed on a syringe.

The broken line showing a syringe in FIG. 8, and the cannula extending from the syringe, is for the purpose of illustrating the environment of the cannula securing device and form no part of the claimed design.
